UNITED STATES PATENT OFFICE

WILLIAM T. DEACON, OF RICHMOND HEIGHTS, AND HARRY F. PERKINS, OF CLAYTON, MISSOURI, ASSIGNEES TO METALFOILS, INCORPORATED, OF ST. LOUIS, MISSOURI, A CORPORATION OF MISSOURI

MACHINE FOR LOCK-SEAMING SHEET METAL

Application filed June 6, 1931. Serial No. 542,565.

This invention relates to a lock-seaming machine of the particular type described in our pending application for patent Serial No. 457,886, filed May 31, 1930, which is 5 primarily adapted for use in the operation of joining strips or sheets of metal foil that are used to form a metallic protective sheathing for a roof, wall or other surface.

One object of our present invention is to 10 improve the means that is employed in such a machine for drawing together and straightening out, the co-acting upstanding flanges on two adjacent pieces of foil, preparatory to the operation of curling, bending or rolling said flanges into interlocking relation to 15 produce a locked seam.

Another object is to provide a lock-seaming machine of the general type mentioned, that is equipped with means for producing 20 a locked seam which is of such shape or form that it reduces to a minimum the tendency of water or foreign matter to collect at one side of said seam.

And still another object is to produce a 25 die structure by which pieces of metal foil can be lock-seamed quickly, effectively and without liability of cracking or rupturing the foil.

Figure 1 of the drawings is a top plan 30 view of our improved lock-seaming machine.

Figure 2 is a side elevational view of said machine.

Figure 3 is a front elevational view of the plow.

Figure 4 is a bottom plan view of the "plow" used to draw together and straighten out, the flanges or co-acting portions on two adjacent pieces of foil, preparatory to deforming said portions to produce a locked 40 seam.

Figure 4^a is a bottom plan view of the "plow" whose cooperating members are held together by magnetism.

Figure 5 is a vertical sectional view of the 45 plow, taken on the line 5—5 of Figure 3.

Figure 6 is a vertical transverse sectional view of the plow, taken on the line 6—6 of Figure 5.

Figure 7 is a bottom plan view of the tail 50 die that imparts a substantially wedge shape

to the locked seam produced in the die structure of the machine.

Figure 8 is a front elevational view of said tail die, taken on the line 8—8 of Figure 2.

Figure 9 is a rear elevational view of said 55 tail die, taken on the line 9—9 of Figure 7, looking in the direction indicated by the arrow.

Figure 10 is a fragmentary transverse sectional view of the pressing roller or equivalent means that is used to flatten down the 60 seam produced by the die structure.

Figure 11 is a vertical longitudinal sectional view of the die structure; and

Figures 12, 13 and 14 are vertical cross- 65 sectional views of the first, second and third dies of the die structure, taken on section lines of corresponding number on Figure 11.

Our improved lock-seaming machine is composed of a frame or body portion A, preferably shaped so that it will serve as a handle 70 that can be grasped by the operator who uses the machine, and a die structure carried by said frame and designed so that when the machine travels forwardly over two strips of metal foil y, provided with upstanding flanges x that are disposed in substantially parallel relationship, as shown in Figure 3, said die structure will cause said flanges to be deformed in such a way as to produce a 75 locked seam that is gas-tight and liquid-tight. Said die structure is articulated, jointed or made up of a number of relatively short die elements pivotally connected together, and is herein illustrated as comprising a plurality 80 of dies 1, 2 and 3 and a tail die 4. The dies 1, 2 and 3 are mounted on a flexible support 5 and have their adjacent or abutting end portions connected together by pivots or joints 3^a that maintain said dies in alignment 85 but still permit them to move angularly relatively to each other sufficiently to conform to a concave surface or to a convex structure.

The internal spaces or cavities of said dies are so shaped and proportioned that the flanges x 90 will be progressively curled, due to the contact or engagement of said flanges with the walls of a cavity which changes gradually in shape and dimensions. As shown in Figures 11—12, 13 and 14 the cavity of the die 95 100

- structure comprises a circular portion of progressively increasing dimensions that merges into a straight sided slot of progressively decreasing dimensions, and the said circular portion has a gradually receding angle. Accordingly, the movement of the die structure longitudinally of the coacting flanges on the pieces of foil, causes said flanges to be curled and lock-seamed together without liability of cracking or rupturing the foil. The tail die 4, hereinafter described in detail, is rigidly attached to the rear end of the die 3. At the front end of the frame A of the machine are two balancing rollers B carried by arms 6 that branch laterally from the frame A, and at the rear end of said frame is a cross bar or pair of laterally-projecting arms 7 that carry guiding rollers C which will be hereinafter described.
- As previously stated, our improved machine is intended to be used for joining strips of metal foil whose longitudinal edge portions have been turned upwardly so as to produce substantially parallel flanges on said strips. Accordingly, the machine is preferably provided at its front end with a means for drawing said flanges together, straightening out said flanges and removing wrinkles from same, and presenting said flanges properly to the die structure. In the machine herein illustrated the means just referred to consists of an apparatus, referred to for convenience as a "plow", and designated as an entirety by the reference character D. Said plow is composed of two members 8 and 8^a shaped so as to form in effect a vertically-disposed, elongated groove or guideway that will receive the co-acting flanges or upstanding portions α on two adjacent strips of foil γ , as shown in Figure 3, when the machine is moved longitudinally of said strips to the left, looking at Figure 2. The members 8 and 8^a of the plow are mounted on the horizontally-disposed portion 9 of a substantially angle-shaped bracket arranged at the front end of the frame A of the machine, and in order that the plow may be raised and lowered, said bracket is connected to the frame A in such a way that it can be adjusted vertically. In the machine herein illustrated the vertically-disposed portion 10 of the bracket is provided with a slot 11 (see Figure 3) that receives the shank of a clamping screw 12 mounted at the front end of the frame A of the machine.
- The co-operating members 8 and 8^a of the plow are of substantially angle shape in cross section, as shown in Figure 3, and the horizontal leg of the member 8 is rigidly connected by fastening devices 13 to the horizontally-disposed portion 9 of the supporting bracket. The other member 8^a of the plow is mounted so that it is capable of rocking slightly about a vertical axis, but will be normally pressed towards the sta-

tionary member under sufficient pressure to cause the rear end portions of the members 8 and 8^a to co-act or co-operate with each other to draw the flanges α on the strips of foil together and also smooth out any irregularities in said flanges. As shown in Figure 4, the movable member 8^a of the plow can be joined to the horizontally-disposed portion 9 of the supporting bracket by means of a pivot 14 arranged at the front end of the member 8^a, and a spring 15 or other suitable pressure-producing means can be used to move the rear end portion of the member 8^a laterally towards the stationary member 8 of the plow. Instead of using a spring or other resilient means for causing the co-operating members of the plow to exert pressure on the flanges α of the strips of foil in a direction to draw said flanges together and smooth them out, the members 8 and 8^a of the plow can be magnetized, as indicated in Figure 4^a, in such a way that the rear end portions of said members will have a natural tendency to remain in contact with each other, and accordingly, will exert pressure on the upstanding flanges of the strips of foil when the machine is moved forwardly over said strips. Usually, the slot or guideway formed by the members 8 and 8^a will be approximately one-fourth of an inch in width, at its front end, and the opposed vertically-disposed faces on said members that constitute the side walls of said guideway will be curved gradually from their front ends towards their rear ends, thereby producing a plow that will adjust itself automatically to the co-acting flanges on the strips of foil and cause said flanges to be progressively smoothed out and straightened when the machine is moved forwardly over two strips of foil that are being lock-seamed together.

In joining pieces of metal foil by curling, bending or deforming co-acting flanges or portions on the foil, to produce a locked seam, the lock-seaming operation will be greatly facilitated if a lubricating medium is applied to the portion of the foil which comes in contact with the curling or deforming die of the machine, particularly with a portion of the die structure that is of circular or substantially circular shape in cross section. Accordingly, we have provided our improved machine with means for progressively applying a lubricating medium to the upstanding flanges α on the strips of foil, prior to the entrance of said flanges into the die structure of the machine. While this highly desirable result may be attained in various ways without departing from the spirit of our invention, we prefer to mount an oil cup or other suitable lubricant holder E on the supporting bracket at the front end of the machine which carries the plow, and provide the stationary member 8 of the plow with lubricant distributing ducts 16 disposed so that

a lubricating medium will be supplied to a plurality of outlet ports 17 in the rear end portion of the vertical face of said member 8, as shown in Figure 5. In the machine 5 herein shown the ports 17 are so arranged that the lubricating medium will be applied in the form of drops adjacent the top edge of the flange α which forms the top side or upper portion of the locked seam.

10 As previously stated, balancing and guiding rollers are arranged at both ends of the frame A of the machine. The rear rollers C are relied upon to prevent or overcome the tendency of the machine to side slip or move 15 laterally, particularly when the machine is being used by an inexperienced workman, and said rear rollers C are arranged some distance outwardly from the center longitudinal axis of the machine as shown in Figure 20 1, so as to hold the rear end of the machine steady by providing bearing members thereon that engage the supporting surface at widely separated points. Preferably, each 25 of the rollers C is journaled in the lower end of a vertically-disposed spindle 18 with which a spring 19 is combined, so as to insure the roller being held yieldingly in engagement with the surface on which the roller travels.

30 The tail die 4 of the die structure of the machine is a new feature that greatly improves the operation of the machine. Said tail die is used primarily to prevent the locked seam produced by the die structure, from 35 bending in the wrong direction when said seam is flattened down by the pressing roller or equivalent means F that is arranged at the rear end of the die structure. As shown 40 in Figures 7, 8 and 9, the tail die 4 is provided on its underside with a cavity 20 that changes gradually from a circular cross section located at the front end of the die to a substantially horizontally-disposed, wedge-shaped cross section located near the rear end 45 of the die, said cavity 20 being disposed at a slight angle relatively to the longitudinal axis of the die structure, so as to exert a lateral thrust or sidewise thrust on the seam and also tend to tighten the same. The tail 50 die 4, in traveling forwardly over the substantially circular-shaped seam produced by the dies 1, 2 and 3, in front of the tail die, causes said seam to be partially flattened, converted into a substantially wedge shaped 55 cross section, and caused to lie at one side of the dividing line between the flanges α on the strips of foil. Consequently, when the pressing roller F or equivalent means acts 60 upon the seam produced in the die structure, there is no tendency for said seam to bend in the wrong direction, for example, to the left instead of to the right, as is liable to occur when a pressing roller or other equivalent flattening means engages a locked seam 65

of substantially circular shape in cross section.

The pressing roller, shoe or other equivalent means F that is used to flatten down the seam produced in the die structure may 70 have a contacting surface of various shapes. We prefer, however, to provide said roller F with a contacting surface 21 of substantially convex shape, or crowned a few thousandths of an inch, as shown in Figure 10, so that the 75 flattening operation will not cause the metal foil to be strained or ruptured by producing too sharp a bend in same.

Having thus described our invention, what 80 we claim as new and desire to secure by Letters Patent, is:

1. A machine for joining pieces of metal provided with co-acting upstanding flanges, comprising a die structure constructed so as to progressively curl or bend said flanges into 85 interlocking engagement so as to produce a locked seam, when the machine is moved longitudinally of said flanges, and a device mounted on said machine in advance of said die structure and composed of a stationary 90 member and a co-operating movable member, said members being provided with opposed portions that form a slot or guideway whose walls smooth out said flanges and draw them together prior to said flanges being engaged 95 by said die structure.

2. A machine for joining pieces of metal provided with co-acting upstanding flanges, comprising a die structure constructed so as to progressively curl or bend said flanges into 100 interlocking engagement so as to produce a locked seam, when the machine is moved longitudinally of said flanges, and a device in advance of said die structure composed of a stationary member and a movable pressure member, provided with co-acting portions that exert pressure on said flanges in a direction to straighten out irregularities in the same, prior to said flanges being engaged by said die structure.

3. A machine for lock-seaming pieces of metal provided with co-acting upstanding flanges, comprising a die structure constructed so as to progressively curl or bend said flanges into interlocking engagement so 110 as to produce a locked seam, when the machine is moved longitudinally of said flanges, a device in advance of said die structure, comprising a stationary member and a movable member having opposed portions that are 115 adapted to engage said flanges, smooth out wrinkles in same and press said flanges together prior to said flanges being engaged by said die structure, and means for permitting sufficient relative movement between said members to cause said members to automatically accommodate themselves to the combined thickness of the flanges.

4. A machine for joining pieces of metal provided with co-acting upstanding flanges, 120

- comprising a die structure constructed so as to progressively curl or bend said flanges into interlocking engagement so as to produce a locked seam, when the machine is moved longitudinally of said flanges, a device in advance of said die structure composed of a stationary member, and a pivotally mounted member provided with opposed portions that are adapted to engage the outside faces of the flanges before said flanges are engaged by the die structure, and means which tends to force the free end of said pivotally mounted member towards said stationary member.
5. A machine for joining pieces of metal provided with co-acting upstanding flanges, comprising a die structure constructed so as to progressively curl or bend said flanges into interlocking engagement so as to produce a locked seam, when the machine is moved longitudinally of said flanges, a device in advance of said die structure provided with a stationary portion and a movable portion that form an elongated guideway whose side walls engage and exert pressure on said flanges preparatory to the beginning of the deforming operation of said flanges by said die structure, and means for enabling said device to be adjusted vertically.
10. 6. A machine for joining pieces of metal provided with co-acting upstanding flanges, comprising a die structure constructed so as to progressively curl or bend said flanges into interlocking engagement so as to produce a locked seam, when the machine is moved longitudinally of said flanges, a horizontally-disposed support on the frame of the machine arranged in advance of the die structure, a device for removing wrinkles from said flanges and pressing them together prior to the beginning of the deforming operation, said device being carried by said support and composed of two members provided with opposed vertically-disposed portions that form an elongated guideway through which said flanges travel as the machine moves forwardly, means for permitting one member of said device to have a slight rocking movement relatively to the other member of the device, and means for causing said rockable member to exert pressure on said flanges.
15. 7. A machine for joining sheets of metal provided with co-acting upstanding flanges, comprising a frame adapted to be moved longitudinally of said sheets over said flanges, a die structure on said frame for progressively curling or bending said flanges to produce a locked seam, said die structure being articulated so as to adapt it to sheets that are flat or curved, a tail die at the rear end of said die structure that imparts a substantially wedge-shaped cross section to the seam, and means located at the
20. rear of the tail die for pressing down said seam.
8. A machine for joining pieces of metal provided with co-acting upstanding flanges, comprising a frame adapted to be grasped by the hand of the operator and moved forwardly over said flanges, a flexible die support arranged under said frame, an articulated die structure carried by said flexible support for progressively curling or bending said flanges to produce a locked seam, said structure comprising a tail die shaped so as to impart a substantially wedge-shaped cross section to the seam, and a means on said frame located at the rear of said tail die for pressing down said seam.
25. 9. A machine for lock-seaming pieces of metal provided with co-acting upstanding flanges, comprising a frame adapted to be grasped by the hand of the operator and then moved forwardly longitudinally of said flanges, a means located at the end of said frame for smoothing out irregularities in said flanges and drawing said flanges together prior to the beginning of the operation of deforming or bending said flanges, an articulated die structure on said frame comprising a tail die having a substantially wedge-shaped cavity, for progressively curling or bending said flanges so as to produce a locked seam, a means located at the rear end of the machine for pressing down the seam, and means mounted on said frame for progressively applying a lubricating medium to said flanges before said flanges are engaged by the die structure.
30. WILLIAM T. DEACON.
